(57) **CLAIM**

I claim the ornamental design for a handheld cyclonic vacuum, as shown and described.

DESCRIPTION

FIG. 1 is a left view thereof;

FIG. 2 is a front end view thereof;

FIG. 3 is a rear end view thereof;

FIG. 4 is a top view thereof;

FIG. 5 a bottom view thereof.

FIG. 6 is a right view thereof; and,

FIG. 7 is perspective view of a handheld cyclonic vacuum incorporating the inventive design.
